Seymour Lindenbaum, New York, N. Y.

Application July 28, 1933. Serial No. 48,857

Term of patent 3½ years

To all whom it may concern:

Be it known that I, SEYMOUR LINDENBAUM, a citizen of the United States, residing at 845 West End Avenue, New York, county of New York, State of New York, have invented a new, original, and ornamental Design for a Lace Textile Fabric or a Similar Article, of which the following is a specification, reference being had to the accompanying drawing, forming part thereof.

The figure is a plan view of a lace textile fabric or a similar article, showing my new design.

The dot and dash lines in the drawing outline

the design unit, which unit is repeated in regular succession, as indicated by the extensions beyond the unit boundaries. The interrupted cross hatching on the figures forming the design represents substantially solid material superimposed upon a background of open net-work.

I claim:
